UNITED STATES PATENT OFFICE.

JOHN AMBROSE FLEMING, OF LONDON, ENGLAND, ASSIGNOR TO THE RADIO CORPORATION OF AMERICA, OF NEW YORK, N. Y., A CORPORATION OF DELAWARE.

THERMIONIC DEVICE.

Application filed November 6, 1919. Serial No. 336,029.

To all whom it may concern:

Be it known that I, JOHN AMBROSE FLEMING, a subject of the King of Great Britain, residing at University College, Gower Street, London, England, have invented a new and useful Improvement in Thermionic Devices, of which the following is a specification.

My invention relates to improvements in the construction of thermionic devices such as are frequently used as detectors of electric oscillations, and to the mode of using the same.

The invention is illustrated by the accompanying drawings, Figure 1 of which is a diagram showing in its simplest form a thermionic device constructed in accordance with my invention, Figure 2 shows a preferred form of construction, Figure 3 is a section through the filament and adjacent parts, Figure 4 is a section of an alternative construction, Figure 5 is a diagram showing the arrangement when my device or valve is used as a receiver of wireless waves, Figure 6 is a diagram of a modified arrangement and Figure 7 is a diagram showing two valves connected in parallel.

In Figure 1, A represents a vacuous bulb; in this bulb are a filament B, a plate C and two other plates D. The filament B may be of tungsten or tantalum or other suitable metal, or else of carbon, and its ends are connected to a battery E by which it can be rendered incandescent. Seeing that the plate C may be considered as collecting the electrons emitted from the filament, I will call it a collecting plate. To draw the electrons thereto it is connected to the positive end of the filament through a current responsive device F which may be an indicating instrument such as a galvanometer, or may be a relay adapted to close a circuit or perform some other useful function.

When the filament is rendered incandescent negative electricity escapes from the filament and passes across the vacuous space into the plate C and then returns by the external circuit passing through the instrument F to the positive terminal of the filament. This current is called the thermionic current.

If now the plates D, which I will call po-

tential plates, are connected to some source of high or low frequency alternating or even direct potential this variation of potential will cause a sudden and marked diminution in the thermionic current, which can be observed in the instrument F or can be utilized to actuate a relay.

Figure 2 shows a preferred form of valve constructed in accordance with this invention. A is a glass bulb which is highly exhausted of its air by processes well known and used by all incandescent lamp and thermionic valve manufacturers. Into the neck of the bulb is sealed a glass tube G closed at its inner end through which are sealed six platinum wires to which are connected inside the bulb six nickel wires between two of which is stretched a straight filament B of tungsten, tantalum, carbon, or other suitable material, while the other four serve as supports to a pair of collecting plates C and a second pair of plates D. These plates are in the form of segments of cylinders and have their convex sides towards the filament. It is desirable that the plates should be placed close to the filament with their nearest surfaces about 2 to 3 millimetres or so and all at approximately equal distances. The plates are made of sheet metal preferably nickel or platinoid or any other not too fusible metal not easily oxidized.

Since the filament tends to expand then incandescent means, such as a spring H, should be provided for keeping it from becoming so slack or bent as to touch any of the plates.

It is not necessary to have a single straight filament for the incandescent electrode. It may be in the usual loop form but in any case it must be so held and retained that in no case does it touch the curved metal anodes or come nearer to any one of them.

The ends of the platinum leading-in wires are connected inside the tube G to copper wires which are insulated by having slipped over them thin glass tubes I.

The parts B, C, D, G, H and I, are assembled together and the tube G is then sealed into the bulb which is then exhausted of its air in the usual manner for making "hard" valves. I desire it to be understood, however, that this particular mode of hold-

ing the plates and filament on a stem does not form a necessary part of my invention but that any other convenient method may be adopted. For instance, the four curved 5 plates may be carried on platinum wires sealed through the sides of a cylindrical bulb, and the filament to be rendered incandescent may pass down the axis of the bulb as shown in Figure 4.

10 Figure 5 shows diagrammatically one of my valves connected up for use in the detection of wireless waves incident upon an aerial K coupled to an oscillatory circuit L which is connected to the plates D. The incidence of the waves on the aerial will produce a difference of potential between the 15 two plates D and this will cause the thermionic current through the device F to diminish. This device F may be a galvanometer, but preferably I employ a telephone magneto receiver of which the coil is connected directly between the collecting plates C and the positive end of the filament, as illustrated, or in any other suitable manner, such as by means of a coupling transformer. The sudden decrease in the thermionic current due to the incidence of the 20 waves will cause a sound to be heard in the telephone. If the waves used are damped 25 trains then as long as they fall on the aerial a continuous sound will be heard in the telephone and this sound can be cut up into Morse code signals by a key in the distant transmitter circuit. The device F may also 30 be a relay adapted to close a local circuit when a difference of potential is impressed upon the plates D. This relay may work 35 a Morse inker or other telegraphic recorder or ring an electric bell, light an electric lamp or start an electric motor so as to move some mechanism.

In the modified arrangement shown in Figure 6 the collecting plates C, C, are connected to a relay M adapted to close the circuit of a battery N and an instrument O such as a call bell, lamp or motor. The plates D, D, are connected to opposite ends of a high resistance Q inserted with a high voltage battery R in the circuit of the plate 40 S and filament T of a three-electrode valve U the grid V and filament T of which are connected in the well known manner which needs no description here to an oscillatory circuit L coupled to an aerial K. A small 45 current from the battery R normally flows through resistance Q and from plate S through the vacuum to filament T and this creates between the plates D, D a difference of potential sufficiently great to reduce the 50 thermionic current from the filament B to the collecting plates C, C. When, however, waves fall on the aerial K they give rise to a negative charge on the grid V and this 55 reduces the current flowing in the circuit Q S T. The difference of potential between

the plates D, D, is therefore reduced and the thermionic current through relay M is increased sufficiently to close the local circuit through the instrument O. In cases in which the available variation of potential 70 or current is very small the necessary difference between the plates D, D, can be obtained by interposing a transformer between the plates and the circuit containing the plate S and filament T.

75 The above described thermionic detector is thus well adapted for operating a call signal which may call attention to the fact that radiotelegraphic messages are about to arrive and may also be used for various other 80 purposes, for example, to steer a boat or aeroplane electrically by wireless waves sent from a distance.

I have found that the above described 85 thermionic instrument responds not only to high frequency alternating but also to direct or unidirectional potential differences applied to the potential plates D, D, and that such low frequency potential differences also effect a reduction in the thermionic 90 current passing to the collecting plates C, C, from the filament. Hence there is a variety of uses of such a detector in alternating current measurements. For example, I can utilize the device as a detector in an 95 alternating current Wheatstone bridge either by direct connection across the arms of the bridge or by coupling to a diagonal coil connected across the arms of the bridge.

100 It is clear also that a number of these detectors can be operated in parallel, the thermionic currents of a number of bulbs passing through one and the same current detecting instrument and the potential plates of all bulbs being influenced simultaneously by the same source of alternating 105 potential as shown in Figure 7.

When using the above described thermionic instrument as a detector in wireless telegraphy, with an air core transformer in 110 the receiving circuit by using a suitably wound transformer I can increase the potential difference applied to these plates in a well-known manner.

115 In the same way when employing low frequency potential differences I can step them up by interposing a suitably wound low frequency transformer with its high tension terminals connected to the potential plates.

120 What I claim is:—

1. A thermionic device comprising a vacuous bulb, a filament, a pair of collecting plates and a pair of potential plates, the four plates being arranged substantially 125 symmetrical to and closely surrounding the filament.

130 2. A thermionic device comprising a vacuous bulb, a filament, a pair of collecting plates and a pair of potential plates, each

of said plates being in the shape of a segment of a cylinder, said plates being arranged substantially symmetrical around the filament with their convex sides nearest 5 to the filament.

3. A thermionic device comprising a vacuous bulb, a filament therein, means for heating the filament and four metal plates arranged symmetrically around the filament 10 and in close proximity thereto, a current responsive device connected to one pair of opposite plates and to the filament and means for applying a difference of potential to the plates of the other pair.

15 4. The combination of a thermionic device comprising a vacuous bulb, a filament, a pair of collecting plates and a pair of potential plates, the four plates being arranged substantially symmetrical around 20 and in close proximity to the filament with a receiving circuit connected to the potential plates, a relay connected to the collecting plates and to the filament and a calling device cooperating with said relay.

25 5. The combination of a vacuous vessel, an electron emitting filament therein, a battery having its two poles connected to the two ends of the filament, a pair of potential plates within the vessel, means for applying a variable potential to these plates, 30 an electron collecting plate also within the vessel, a circuit connected between the collecting plate and one end of the filament and a current responsive device cooperating with 35 said circuit.

6. The combination of a vacuous vessel, an electron emitting filament therein a battery having its two poles connected to the two ends of the filament, a pair of potential plates within the vessel, means for applying a variable potential to these plates, 40 an electron collecting plate also within the vessel, a circuit connected between the collecting plate and the positive end of the filament and a current responsive device cooperating with said circuit.

45 7. The combination of a vacuous vessel, an electron emitting filament therein, a battery having its two poles connected to the two ends of the filament, a pair of potential plates within the vessel, means for applying a variable potential to these plates, a pair 50 of electron collecting plates also within the vessel, a circuit connected between the collecting plates and one end of the filament and a current responsive device cooperating with said circuit.

55 8. The combination of a vacuous vessel, 60 an electron emitting filament therein, a battery having its two poles connected to the two ends of the filament, a pair of potential plates within the vessel, means for applying a variable potential to these plates, a pair 65 of electron collecting plates also within the vessel, a circuit connected between the col-

lecting plates and the positive end of the filament and a current responsive device cooperating with said circuit.

9. The combination of a vacuous vessel, 70 an electron emitting filament therein, a battery having its two poles connected to the two ends of the filament, a pair of potential plates arranged within the vessel opposite one another on either side of the filament, a pair of electron collecting plates arranged 75 within the vessel opposite one another on either side of the filament, a circuit connected between the collecting plates and the positive end of the filament and a current responsive device cooperating with said circuit.

10. The combination of a vacuous vessel, 80 an electron emitting filament therein, a battery having its two poles connected to the two ends of the filament, a pair of potential 85 plates within the vessel, means for applying a variable potential to these plates, an electron collecting plate also within the vessel, each plate being in the form of a segment of a cylinder and having its convex side towards the filament and a current responsive 90 device connected between the collecting plate and one end of the filament.

11. The combination of a vacuous vessel, 95 an electron emitting filament therein, a battery having its two poles connected to the two ends of the filament, an electron collecting plate within the vessel, a current responsive device connected between the collecting plate and the positive end of the filament, a 100 pair of potential plates within the vessel, one on either side of the filament, an aerial, an oscillatory circuit coupled to the aerial and connections between the circuit and the potential plates.

12. The combination of a vacuous vessel, 105 an electron emitting filament therein, a battery having its two poles connected to the two ends of the filament, an electron pair 110 of collecting plates, one on each side of the filament within the vessel, a current responsive device connected between the collecting plates and the positive end of the filament, a pair of potential plates one on each side 115 of the filament within the vessel, an aerial, an oscillatory circuit coupled to the aerial and connections between the circuit and the potential plates.

13. The combination of a vacuous vessel, 120 a filament therein, a battery having its two poles connected to the two ends of the filament, a collecting plate within the vessel, a relay connected between the collecting plate and the positive end of the filament, a local 125 circuit adapted to be actuated by the relay, a pair of potential plates within the vessel, one on either side of the filament, an aerial, an oscillatory circuit coupled to the aerial and connections between the circuit and the potential plates.

14. The combination of a vacuous vessel, a filament therein, a battery having its two poles connected to the two ends of the filament, a pair of collecting plates, one on either side of the filament within the vessel, a current responsive device connected between the collecting plates and the positive end of the filament, a pair of potential plates, one on either side of the filament within the vessel, an aerial, an oscillatory circuit coupled to the aerial and an amplifying device connected to the potential plates and to the circuit.

15. The combination of a vacuous vessel, a filament therein, a battery having its two poles connected to the two ends of the filament, a pair of collecting plates, one on either side of the filament within the vessel,

a relay connected between the collecting plates and the positive end of the filament, a local circuit adapted to be closed by the relay, a pair of potential plates, one on each side of the filament within the vessel, a resistance having one end connected to each of the potential plates, an aerial, an oscillatory circuit coupled to the aerial, a three-electrode valve having its grid and filament connected to the circuit and its anode connected to one end of the resistance and a battery connected between the filament of the three-electrode valve and the other end of the resistance.

In testimony that I claim the foregoing as my invention I have signed my name this 15th day of October, 1919.

JOHN AMBROSE FLEMING.
